[57] CLAIM

The ornamental design for a tongue cleaner, as shown and described.

DESCRIPTION

FIG. 1 is a top plan view of the tongue cleaner of the present invention, the bottom plan view being identical thereto; FIG. 2 is a left side view of the Tongue Cleaner of FIG. 1, the right side elevational view being a mirror image thereof; and,

FIG. 3 is a front elevational view of the tongue cleaner of FIG. 1, the rear elevational view being a mirror image thereof; and,

FIG. 4 is a left side view thereof, shown in bent position.
